UNITED STATES PATENT OFFICE

2,508,417

OSCILLATING RAILWAY SWITCH

Francis W. Orendorff, Missoula, Mont.

Application February 14, 1947, Serial No. 728,485

1 Claim. (Cl. 246—431)

1

The present invention relates generally to railway switches, and more specifically to an improved oscillating railway switch of the rolling pin type for turning out from the main railway line and entering a siding. The primary object of the invention is the provision of a switch structure including a pair of switch rails adapted to oscillate on their longitudinal axis, and in opposite directions, together with operating means therefor, to assure a safe and reliable switch structure that is operable from a switch stand of the ground-throw type. The switch structure is simple in construction and operation, and of the self-cleaning type in that it prevents accumulation of snow and dust, between the switch members and the track rails, and maintains the switch structure in working condition.

The invention consists in certain novel features of construction and combinations and arrangements of parts as will hereinafter be described and more specifically set forth in the appended claim.

In the accompanying drawings I have illustrated a complete physical embodiment of my invention in which the parts are combined and arranged according to one mode I have thus far devised for the practical application of the principles of my invention. It will however be understood that changes and alterations are contemplated and may be made in these exemplifying drawings and mechanical structures, within the scope of my claim without departing from the principles of my invention.

Figure 1 is a plan view of the switch structure for a turnout switch, shown as normally closed.

Figure 2 is a vertical transverse sectional view at line 2—2 of Fig. 1.

Figure 3 is a plan view of the switch according to my invention, set in open position for entrance from the main line.

Figure 4 is a transverse sectional view at line 4—4 of Fig. 3; and Fig. 5 is a similar view at line 5—5 of Fig. 3.

Figure 6 is an enlarged transverse sectional view at line 6—6 of Fig. 1; and Figure 7 is a similar view at line 7—7 of Fig. 1.

Figures 8 and 9 are detail views of the opposed switch rails.

In order that the general arrangement and utility of parts may readily be understood, I have shown in Figs. 1 and 3 a standard track with main line rails 1 and 2 supported upon the cross ties 3 as usual, and in addition the curved or turnout portions 4 and 5 of a siding or side track are illustrated. The switch parts are equipped with the mechanism of my invention, and of course the

2

switch is normally closed as shown in Fig. 1 for main line traffic as shown by the arrows; and in Fig. 3 the switch has been opened to permit entry of traffic to the side track as indicated by the line of arrows.

In carrying out my invention I employ two switch rails 6 and 7 of suitable length and generally of solid cylindrical shape, supported at the inner sides of the two main track sections of rails 10 for simultaneous oscillation or partial turning on their respective longitudinal axes, in the same direction for the closing of the switch and in opposite direction for the opening of the switch.

The switch bars normally lie parallel with the 15 main line rails and depressed below the heads of the main line rails out of the way of the wheels of the rolling stock; and each switch rail is fashioned with a flat normally upper face 8 and longitudinally extending flanges or tongues 9 and 10 of the respective rails. The flange or tongue 9 of rail 6 in Fig. 1 where the switch is closed, is turned to inoperative position, while the flange or tongue 10 of the switch rail 7 forms a continuation of the main line track.

25 In Fig. 3 where the switch is open, the flange or tongue 9 of the switch rail 6 is aligned with the siding rail 4, and the flange 10 of the rail 7 is turned away leaving the main line rail 2 and siding rail 5 aligned for passage of the rolling stock.

30 At its far or outer end each of the switch rails is fashioned with a preferably integral trunnion or axis pin 11 and these trunnions are swiveled in bearing brackets 12 and 13 that are bolted to the webs of the respective main line rails 1 and 2, and they project laterally toward the center of the track.

35 On the ends of the switch rails located at the entrance to the switch they are equipped with trunnions or swivel pins 14, 14 journaled to turn in bearing bores that extend transversely through a cross beam 15 that extends across the track and is rigidly bolted at its ends to the inner faces of the webs of the main line rails 1 and 2 that are drilled for this purpose.

40 Between the cylindrical bodies of the switch rails and their trunnions 14 they are fashioned with cylindrical winding and unwinding spindles 16, and a pair of springs 17 and 18 are coiled about a portion of the spindles. These spiral springs 45 17 and 18 each has one end anchored to a spindle and its other end anchored to the cross beam 15, so that the switch rails on their longitudinal axes in the same and in opposite directions, to re-set and restore the switch to closed position.

45 The switch rails are oppositely oscillated

against tension of the springs, to throw open the normally closed switch preferably from a switch stand of the ground throw type to which an operating rod 19 in Fig. 3 is connected, and the rod is pivoted at 20 to a pivot plate 21 of the bell crank lever type that is pivotally mounted on a vertical axis 22 alongside and exterior of the track rails.

At 23 one arm of the bell crank lever is pivoted with a slotted connection to a transversely arranged slide bar 24 that is mounted to slide under one of the rails and between the rails of the track in spaced bearings or brackets 25 that are rigidly mounted upon the cross beam 15.

This slide bar forms a long link of an endless operating chain 26 that is coiled at 27 and 28 on the spindles 16, 16 of the switch rails, and the inwardly extending ends of the chain are attached at 29 and 30 to the slide bar or long link 24. From this description taken in connection with my drawings it will be apparent that when the switch lever is thrown the coiled portions of the chain turn the switch rails in the same direction to open the switch, and it is then secured in open position for entry of rolling stock to the siding. Afterwards, of course the switch bars are rolled back to closed position, the switch rails are turned in the opposite direction and the switch arm or lever is locked as usual.

Having thus fully described my invention, what I claim as new and desire to secure by Letters Patent is:

In a railway switch, the combination with a

pair of laterally spaced track rails, and a cross beam rigidly attached to the inner sides of the webs of the track rails, of a pair of switch rails of generally cylindrical shape each having a spirally arranged longitudinal guide flange, end trunnions on the switch rails journaled in bearings of the cross beam, bearing brackets mounted on the track rails and end trunnions on the switch rails journaled in said brackets, each of said switch rails having a cylindrical spindle, a spring coiled about each spindle having its ends anchored to a spindle and to said cross bar for turning the switch bars in opposite directions, an endless chain having coils about said spindle, a slide bar mounted on the cross beam and forming a long link of the chain, and means for shifting the slide bar transversely of the track to open the switch.

FRANCIS W. ORENDORFF.
